UNITED STATES PATENT OFFICE.

JAMES F. MCINTIRE, OF DETROIT, MICHIGAN, ASSIGNOR TO UNITED STATES RADIATOR CORPORATION, OF DETROIT, MICHIGAN, A CORPORATION OF NEW YORK.

FURNACE.

1,207,777.

Specification of Letters Patent. Patented Dec. 12, 1916.

Application filed March 18, 1916. Serial No. 85,047.

To all whom it may concern:

Be it known that I, JAMES F. MCINTIRE, a citizen of the United States of America, residing at Detroit, in the county of Wayne 5 and State of Michigan, have invented certain new and useful Improvements in Furnaces, of which the following is a specification, reference being had therein to the accompanying drawings.

10 The invention relates to furnaces, and has more particular reference to constructions employed in connection with water heaters or steam generators.

It is the object of the invention to obtain 15 increased efficiency, and to this end the invention comprises the novel means employed for securing more complete combustion of the fuel and the advantageous utilization of the heat generated thereby.

20 The invention further comprises various features of construction as hereinafter set forth.

In the drawings: Figure 1 is a longitudinal section through the furnace substantially on line $x-x$ Figs. 2 and 3; Fig. 2 is a horizontal section thereof; Fig. 3 is a cross section on line $y-y$ Fig. 1; and Fig. 4 is a similar section on line $z-z$.

25 In the construction of boilers for the heating of water or the generation of steam, it is usually an aim to secure the maximum amount of heating surface within given space limits. This is not always advantageous, as the contact of the combustible 30 gases with the comparatively cold surface often lowers the temperature to below the ignition point, resulting in imperfect combustion. Furthermore, as usually constructed there is not a complete commingling of the combustible gases with the air 35 for supporting combustion until after the temperature has been lowered to under the combustion point.

To overcome the defects just described, I 40 have devised a construction of furnace in which a very complete commingling of the combustible gases with air is effected before said gases are brought into contact with any considerable amount of the surface to be heated. I have further provided ignition 45 means for the commingled gases, which in the normal operation of the furnace is effective whenever there is a generation of gas; as for instance, when fresh fuel is placed on the fire. Thus my improved con-

struction secures more complete combustion of the fuel, and the heat thus generated is subsequently effectively used in connection with the heating surface of the boiler.

In the specific application of my invention which is illustrated, the furnace and boiler is composed of a series of apertured hollow sections placed adjacent to each other, the apertures forming the combustion chamber and flue spaces, while the chambers 60 within the sections contain the water and steam. Constructions of this type have been heretofore used, and it has been the practice to divide the flue spaces into small sections by crossing water channels so as to secure 65 the maximum amount of heating surface. With my improved construction, however, a considerable amount of this heating surface has been dispensed with and the combustion chamber and flue spaces enlarged to secure 70 better combustion, which in turn secures greater efficiency even with a reduced heating surface.

In detail, A are the furnace sections, all of 75 which are apertured at B and B' to form flues for the products of combustion, while the forward sections are centrally cut away at C to form the furnace chamber. At the bottom of this chamber are arranged grates D supported in an ash-pit section or base E, 80 and a front section A' forms a closing wall provided with fuel doors F. There is also an imperforate rear section A², which forms the rear wall of the furnace chamber, while the depending water-legs G upon opposite 85 sides of the cut-away portion form the side walls of the furnace.

At the inner end of the portion of the furnace chamber which is directly above the grates is a bridge wall, which is preferably 90 a hollow water section H formed integral with one of the furnace sections A³. Above this partition or wall H is a restricted opening I, preferably a pair of such openings I and I' upon opposite sides of a central vertical water-wall J also integral with the section A³.

As shown, the furnace is composed of 95 pairs of sections arranged in the same plane on opposite sides of the center, and the wall J is formed of adjacent abutting edges of the pair of sections. Directly in the rear of the partition H and apertures I I', and preferably in the plane of the next adjacent boiler section, is a second wall or partition 100

J, but this instead of being formed integral with the boiler section and of a hollow water-wall, is formed of a refractory material, such as fire-brick or tile. Furthermore, the aperture through this wall for the passage of the gaseous products of combustion, instead of being opposite the apertures I I' and running transversely of the furnace, is arranged at the center in the form of a comparatively narrow slot J' extending vertically. Thus there is formed between the walls or partitions H and J a commingling chamber in which the gases passing through the apertures I and I' are compelled to pass laterally in both a vertical and horizontal direction to find exit through the slot J', and during this transverse movement the air and combustible gases are thoroughly commingled. The rear wall J being of refractory material and being exposed to the heat of combustion, will soon acquire a comparatively high temperature and will maintain a considerable degree of heat, even during the intervals between the feeding of the fuel when there is the least amount of flame. On the other hand, when a fresh supply of combustible gas is formed and passes through the commingling chamber the wall J will form a means of igniting the commingled gas and air as it passes toward the slot J'.

In rear of the wall J the sections are cut-away to form a chamber K of sufficient size for proper combustion of the gases, which then pass upward through openings L into the side flues B, thence forward and through openings M into the central flue B', through which they pass to the rear and to the stack connection.

With the furnace constructed as described, in operation, when the fuel is first ignited upon the grates D it will burn in the chamber C, the gaseous products passing outward through the apertures I and I', commingling chamber N and slot J' into the chamber K, and thence to the flues B and B'. In passing the wall J the latter is heated, so that in a short space of time the flame will pass through the chamber N and slot J' into the chamber K. During this passage the gases have acquired a high temperature and as there is an abundance of air, very complete combustion will take place. The heated products of combustion will then pass through the flues B and B' and during transit will give up the greater part of their heat to the water sections.

The object of forming the wall H as a hollow water-wall is to impart greater mechanical strength to this member than would be possible with a refractory material, such as brick or tile. Furthermore, this wall is

subjected to intense heat due to its proximity to the solid fuel upon the grates and therefore would be in danger of burning out if it were not for the water-cooling. On the other hand, the cooling of the wall H does not interfere with the completeness of the combustion of the gases passing beyond this wall, as the wall J maintains its high temperature and will re-ignite the gases should they be cooled by the wall H below the ignition point.

What I claim as my invention is:—

1. In a furnace, the combination with a series of adjacent water sections apertured to form a furnace chamber and connecting flues therein, of a pair of spaced walls extending transversely across the furnace chamber, having non-registering apertures for the passage of the combustion gases therethrough, compelling a transverse movement and commingling of said gases between said walls, one of said walls being a water-wall integral with one of said furnace sections, and the other of said walls being formed of refractory material.

2. In a furnace, the combination with a series of abutting hollow water sections apertured to form a furnace chamber and connecting flues therein, of a hollow water-wall formed integral with one of said sections and extending transversely across the lower portion of said furnace chamber, with an aperture for the passage of gases thereabove, and a refractory wall extending parallel to and in rear of said water-wall, said refractory wall being provided with a vertical comparatively narrow slot for the passage of the gases out of registration with the aperture in said water-wall, and compelling a transverse commingling movement of the gases between said walls.

3. In a furnace, the combination with a series of abutting arched hollow water sections, forming a furnace chamber surrounded with water walls, of grates extending across a portion of said chamber, a hollow water-wall extending transversely across said chamber in rear of said grates, being formed integral with one of said sections and providing a horizontally-extending aperture thereabove for the passage of gases, and a refractory wall built within one of said arched sections in rear of said water-wall and providing a vertically-extending comparatively narrow slot for the purpose described.

In testimony whereof I affix my signature, in presence of two witnesses.

JAMES F. MCINTIRE.
